ATTORNEY.

UNITED STATES PATENT OFFICE.

WILLY WOLF, OF BERLIN, GERMANY.

BUSINESS BOOK.

Application filed December 5, 1924, Serial No. 754,036, and in Germany December 15, 1923.

This invention relates to covers for ledgers or business books of large size, especially of so-called permanent loose leaf ledgers, whereby punched leaves may be filed upon a proper mechanism. Such ledgers have heretofore ordinarily been made from pasteboard and have been provided with an outer covering of cloth, for instance velvet, and with a leather covering at the corners. The filing mechanism of the ledger is almost indestructible, while the book-covers are subjected to heavy wear and especially exposed to destruction at the corners and edges, so that the book-covers must comparatively often be renewed.

Book covers have also been used which, instead of the usually employed cloth coverings are provided with a covering of vulcanized fiber. In this case, however, only extremely thin fiber plates are used which are united by glue with the thicker pasteboard and fastened to the latter by rivets and have sharply cut edges. At the edges the book-covers will be easily damaged, because the fibrous plates are exposed with their cross section at the edges to rough handling and accordingly will be easily reduced to fibers at these places.

This invention has for its object to provide a ledger or book, which employs heavy fiber plates so disposed that a reducing to fibers at the edges will be avoided by providing resistance against wear during handling which will render the book-cover as indestructible as the mechanism serving for the filing of the leaves. By this invention at the same time the advantage will be secured that the manufacture of the book-covers, in spite of their greater durability, will be quite essentially simplified and cheapened, so that besides the technical success also a commercial advantage is obtained which is of the greatest importance for practical purposes.

In the drawing accompanying and forming part of this specification,

Fig. 1 is a side or edge view of a pair of book covers made in accordance with the present invention, showing the same attached to a back member;

Fig. 2 is a plan view thereof;

Fig. 3 is a transverse sectional view, on a smaller scale, illustrating the manner in which the covers are formed and the mold for forming them; and

Fig. 4 is a perspective view of a cover blank showing the same with its edges bent over in accordance with the present invention.

Referring to the drawing, each of the covers is formed of a fiber plate *a*, three of the edges of which are bent upon themselves to provide folds or rebates *a*¹, *a*² and *a*³ for the reception of a suitable stiffening or reinforcing plate of cardboard, wood or other suitable material as hereinafter described.

Believing that the cover can best be described by describing the method of forming it, I have shown in Fig. 3 a suitable mold or form plate *c*. This mold may be simply a plate having a central longitudinal depression into which the fiber plate *a*, after having a predetermined margin around three of its edges wet to soften the same, is forced under suitable pressure, the fiber plate being of greater length and width than said depression, whereby when pressed into the latter the two longitudinal side edges and one end edge will be turned upward to form a boxlike structure having a bottom and three upstanding walls, the height of said walls being greater than the depth of the depression so that said walls will project above the thicker side portions of the mold.

A plate *b* is then placed within the boxlike structure, said plate being of such width and length as to fit snugly within said structure. The mold is provided with three plates *d* of greater width than the thicker portion of the mold, and after the insertion of the plate *b*, the plates *d* are slid on the top surface of the mold toward the center so as to bend over the upwardly projecting edges of the boxlike structure and cause them to lie in contact with the plate *b*. This plate *b* may be the reinforcing or stiffening plate hereinbefore referred to which is left permanently in the cover, or it may be a special plate formed of metal or other suitable material and removable to give place to said permanent reinforcing plate.

After the reinforcing plate has been inserted into position with its edges within the folded over edges of the plate *a* as above described, the space above the reinforcing plate between the opposite turned-over edges of the folds may be filled in with a suitable fillet *e*, thereby to bring the entire side of the cover into a single plane. The fillet *e*

may be glued to the reinforcing plate, and the entire cover may then be provided with a covering of thin fabric or paper.

A pair of covers of the construction above described may be connected by hinges *g* with a back *f*, said back being of well known construction and provided with the usual loose-leaf mechanism, the hinges being preferably inserted between the fiber plate *a* and the reinforcing plate *b*.

The fact that the edges of the fiber plates are folded over results in the formation of book covers having relatively thick rounded edges capable of considerable resistance to

strains to which they may be subjected in 15 the handling of the book.

Having thus described my invention, what I claim is:

A book cover, comprising a fiber plate folded over at three of its edges to form rebates, a reinforcing plate secured at its edges in said rebates, and a fillet overlying said reinforcing plate between said folded over edges whereby the surface of the cover will lie in a single plane.

In testimony whereof I affix my signature.

WILLY WOLF.
